BRAKE MECHANISM FOR BOBBIN
STRIPPERSEdgar A. Terrell, Charlotte, N. C., assignor to The
Terrell Machine Company, Charlotte, N. C., a
corporation of North Carolina

Application September 14, 1931, Serial No. 562,637

17 Claims. (Cl. 192—135)

The invention relates to bobbin cleaners, and especially to machines of the general character disclosed in my United States Patent No. 1,451,239, dated April 10, 1923; and it consists principally in novel and improved means for bringing the machine quickly to rest. Preferably such stopping means is under control of the cover-lid of the machine, acting automatically when the lid is raised to discontinue the driving of the machine and to apply a brake, so that the machine is stopped without appreciable delay, thus avoiding possibility of injury to the operative by contact with moving parts within the casing.

In machines of the class referred to, intended especially for cleaning roving bobbins, the cleaning mechanism is enclosed in a casing having a movable cover, and includes a rotary drum or belt covered with card-clothing to remove waste yarn from the bobbins, which are fed to it by a conveyor. The cover has to be raised at intervals for inspection, removal or repositioning of misplaced bobbins, cleaning, or for other purposes; if at such times the machine is being driven, or continues to run by momentum after the cover is raised sufficiently to give access to the enclosed mechanism, there is some risk of injury to the operative by contact of his hands or clothing with moving parts, and especially with the card-clothing of the cleaning drum or belt. The invention structure prevents such injury by discontinuing application of driving power and applying a brake which promptly brings the toothed drum or belt, and other parts, to rest before the cover is raised far enough to permit access of the operative's hand to such parts of the machine.

A further advantage is the prevention of injury to bobbins or to the cleaning mechanism, by stopping the machine promptly when the cover is raised, as by the entry of two or more bobbins at once, so that two bobbins will not be fed simultaneously to the roll or belt.

Provision is made for adapting the essential features of the invention to different driving means or arrangements, including belt drive from a counter-shaft and individual motor-drive.

In the drawings:—

Fig. 1 is a side elevation of a machine embodying the invention in one form.

Fig. 2 is a side elevation showing principally the drive and brake controlling means, with other parts omitted.

Fig. 3 is a top plan of certain portions of Fig. 2 with parts broken away.

Fig. 4 is a section at 4, 4, Fig. 2, enlarged.

Fig. 5 is a section at 5, 5, Fig. 2, enlarged.

Fig. 6 is a detail in bottom plan view of the brake lever support of Fig. 2.

Fig. 7 is a side elevation of a modification providing for individual motor drive.

Fig. 8 is a side elevation of principal parts of the drive controlling, brake and brake controlling mechanism of Fig. 7, with other parts omitted.

Fig. 9 is a right side elevation of Fig. 8.

Fig. 10 is a left side elevation of principal parts of the controlling means, with other parts omitted.

Fig. 11 is a detail view of the brake shoe fulcrum mounting.

Fig. 12 is a section at 12, 12, Fig. 11.

In cleaning machines of the class contemplated, as disclosed in the above patent and also sufficiently shown in the present drawings, the cleaning mechanism, including a roll or belt faced with card-clothing and a bobbin-feeder or conveyor, is enclosed in a casing 1 which is supported on a lint-collecting box or chamber 4 into which waste or lint removed from the bobbins is discharged by a blower. The casing 1 has a cover 7 hingedly connected at 10. The ends of belts 13 which hold bobbins against the cleaning roll when the cover is closed, are connected to the cover at the outside thereof by tensioning springs 16. The cover has at its free edge a weight-bar 19 to hold, or assist in holding, it in closed position.

The machine as shown in Figs. 1 to 6 is arranged for driving by a belt 22 from a counter-shaft (not shown) and for drive-control by shifting the belt. A gear 25 which drives parts of the cleaner mechanism including the drum, is fixed on the drum shaft 28. The toothed gear rim is housed in a generally-circular guard 31 which is secured to one side of casing 1 by struts 34, and the gear spokes 37 carry the fast pulley 40, the inward cylindrical portion 43 of which constitutes a brake-drum. The loose pulley 46 is revolvably mounted on the shaft, outside the fast pulley. A controlling lever 49 having a handle 52 is fulcrumed at 55 on a frame-bracket 58, and carries a fork 61 for shifting the belt.

To stop the cleaner mechanism promptly after driving is discontinued by shifting the belt to loose pulley 46, brake mechanism is provided, including a brake-arm 64 pivotally mounted on a stud 67 carried by a lug 70 on or supported by guard 31. The arm has an arcuate shoe-portion provided with a liner 73 to cooperate with the brake-drum, or braking surface 43 of the fast pulley. A portion of arm 64 extends through a slot 76 in guard 31, and is connected by a link 79 to one end of a brake-operating lever 82, fulcrumed at 85 in a lug 88 secured to guard 31.

Lever 82 provides for multiplying the pressure applied to brake-shoe 64 which is desirable because of the moderate diameter of the brake-drum, in the arrangement shown. To properly position the brake shoe, or its liner 73, in relation to the drum, with clearance when in off position, (Fig. 1 or 2), link 79 is made adjustable as by means of nuts 94 on its threaded upper end, engaging at opposite faces of the arm-end 97.

10 The action of the belt-shipper lever 49 and of brake-lever 82 are controlled by a stop-lever 100 fulcrumed on a stud 103 secured in a boss 106 on guard 31. The lower arm 109 of this lever has at its lower end a flat cam-member 112, Fig. 4, shaped to provide an approximately vertical curved or arcuate cam-face 115 engaging controlling lever 49 between its fulcrum and the shipper-fork, and another cam-face 118 extending upward at a divergent angle to the general direction of cam-face 115. The cam-face 118 is engaged by a cam-roll 121 mounted on a pin 124 between lugs 127 near the power-end of lever 82. This end of the lever is forked, as shown best in Fig. 5, providing lugs or flanges 130 located at opposite sides of the upright portion of bracket 58 above-mentioned to guide the lever-end and relieve it and its pivot-mounting 85 from strains or distortion due to laterally-acting forces and especially lateral pressure caused by engagement 30 of roll 121 with cam-face 118. The power end of lever 82 is urged upward by a spring 133 connected at one end to a stud or screw 136 in one of the lugs 130 and at the other to the end of fulcrum stud 103, and this spring 133 provides the force 35 which shifts the controlling lever 49 to put the belt on the loose pulley and which applies the brake.

40 The upper arm 139 of stop-lever 100 terminates in a toe or contact-face 142 (see also Fig. 10) which normally engages the outward face of a lever-detent or cam 145 secured to the casing-cover 7 near its free edge. As shown, this detent is in the form of a circular disk having an eccentric hole 148 fitting on a rod 151 projecting from the weight-strip 19 at the free transverse cover edge, and secured in angularly-adjusted position on the rod by a set-screw 154. Such angular adjustment provides for regulating the point in upward movement of the cover at which the stop-lever will be released; also by moving the cam or detent axially on rod 151, the normal or "running" position of the lower end of lever 100 and of its cam-member 112 may be controlled.

45 In normal operation, with the parts in the positions shown in Figs. 1, 2 and 4, the casing-cover 7 is closed; the toe 142 of stop-lever 100 is in engagement with the outer face of detent-cam 145 near an edge thereof; the power end of brake-lever 82 is urged upward by spring 133 and its cam-roll bears against the diagonal cam-face 118 of the detent-lever, urging the lower end of that lever outward (or toward the left, as viewed in Fig. 4); the detent-lever is prevented from moving in the stated direction by engagement of its toe 142 with the detent-cam, and the brake-lever 82 is thus maintained in depressed, brake-releasing position, the link 79 supporting the free end of the brake-arm 64 so that the brake-liner 73 is free of brake-drum 43. In the stated position of stop-lever 100, its cam-face 115 confronting the controlling or belt-shifting lever 49 is in normal retracted position permitting this shifting lever to be in "running" position; that is, fork 61 controlling belt 22 is positioned to hold the belt on the fast pulley 40. The cleaning mechanism is

thus being driven by belt 22 through the fast pulley connected to the drum shaft, and through gear 25 which drives other parts.

When the cover 7 is raised, for any of the purposes referred to, in the first short upward movement of its free edge, detent-cam 145 is withdrawn from the toe or detent-face 142 of lever 100 which is instantly rocked clockwise as viewed in Fig. 4 on its fulcrum 103 by the pressure of cam-roll 121 acting on cam-face 118 under 10 urgency of spring 133; cam-face 115 is thus moved outward, or to the left in Fig. 4, and acts on the controlling or shifting lever to move its fork 61 and thereby to move the belt 22 to the loose pulley 46, discontinuing driving of the 15 cleaning mechanism; immediately thereafter the continued movement of brake-lever 82 on its fulcrum 85 acts through link 79 to pull down the end of brake-arm 64 and apply the brake-liner 73 to braking surface 43 and promptly bring all moving parts of the cleaning mechanism to rest. This occurs before the cover can be raised far enough to give access to enclosed parts, and when the cover is fully opened inspection, adjustment, or other operations may be effected without risk 25 of injury. Also, the machine will be automatically stopped through raising of the cover when two or more bobbins attempt to enter the machine at once, with attendant danger of injury to the bobbins and to the machine parts. 30

After a stopping action the upper end of lever 100 is positioned below (that is, in the plane of) the detent-cam 145. In the proper mode of operation, before the machine is restarted by manipulation of lever 49, the cover is moved to 35 nearly closed position, whereupon the edge of cam 145 engages the upper end of the stop-lever (or of its toe 142). The cover is then so nearly closed that access to parts within the casing is prevented. Lever-handle 52 is then moved in a 40 direction to shift the belt back to the fast pulley; before the belt is so shifted, lever 49 acting on cam-face 115 moves the lower end of this stop-lever inward (toward the machine, or to the right, in Fig. 4), and diagonal cam-face 118 acts on 45 roll 121 to move it and the power end of the brake-lever downward; brake-arm 64 is thus raised, releasing and clearing brake-liner 73 from drum 43; and thereafter continued movement of controlling lever 49 completes the movement of belt-shifter 61, bringing the belt to driving position on the fast pulley. 50

The upper end or toe 142 of stop-lever 100 has in the stated movements been withdrawn from under the edge of the detent-cam, whereupon the cover drops to fully closed position, and the outer face of the cam is again opposed to the contact-face of lever-toe 142 to maintain all parts in normal running position until the cover is again raised. 60

Lever 49 may be moved to shift the belt and stop the machine, at any time, although if the cover remains closed when this is done, the brake is maintained in "off" or inactive position and there is no braking action. 65

A stop may be provided such as a pin 154 set in bracket 58, to engage lever 49 and limit movement of the lever in the "stopping" direction, or at least to prevent over-stroke of the lever which 70 might otherwise throw the belt outwardly off of the loose pulley. A spring 157 is desirably placed about the lever fulcrum screw or stud 55, bearing against the lever or a washer 56, to frictionally resist or control the lever movement, through 75

pressing the lever's hub against the surface of bracket 58.

Figs. 7 to 12 show the machine as arranged for individual motor drive. The motor (not shown) 5 may be in any convenient location, as on the base of the machine or on the floor adjacent the base, and may be connected to drive-shaft 28 in any convenient way. Specifically, as shown, the motor is connected by a belt 160 to a pulley 163 10 fixed on drum-shaft 28, this pulley corresponding to the fast pulley of the previous example, although as here shown, of considerably larger diameter. There is no loose pulley, and driving is controlled by a switch in the motor circuit, this 15 switch being inclosed in a switch-box 166 (Fig. 7) carried by a bracket 169 secured to top-plate 171 of the waste-box 4. A guard-housing 174 is provided for the belt and pulley, as shown in Fig. 7, this being omitted in the other figures. 20 The main or drive controlling lever 177 is in upright position, fulcrumed at 180 on an arm 183 of bracket 169. The handle 186 is at the end of the upper arm 189, and the lower arm 192 of the lever is connected to the switch by any suitable means or linkage 195, details of which are 25 non-essential.

Pulley 163 has the inward portion of its tread arranged as a brake-drum or braking-surface 198, as in the previous example, except that it 30 is of larger diameter, corresponding to the large-diameter pulley 163. For a brake-drum of such large diameter providing in itself a substantial leverage effect in the braking action, a compound-leverage brake-operating mechanism is 35 not required, this being provided in the arrangement of Figs. 1 to 6 because of the relatively small diameter of the braking drum. In the present example, therefore, a single-acting brake-arm or lever 201, with brake-liner 203, is pivotally 40 mounted on a stud 204 carried by a lug or bracket 207 on guard 31. This lever has an extension corresponding to the end structure of lever 82 of Figs. 1 to 6, and acted on by a spring 133 located and connected in a similar way, and 45 also provided with a roller 121 cooperating with the cam-face 118 of stop-lever 100; and this lever is arranged and cooperates with a detent-cam 145 and with the main drive controlling lever 177 as in the previous example, except that in 50 the present case the upright controlling lever has a flange 207 providing a face 210 adjacent and above the fulcrum 180, with which cam-face 115 of lever 100 coacts.

The operation is the same as already described 55 in connection with Figs. 1 to 6, except that in an automatic stopping action, the brake-arm or brake-shoe 201 is acted on directly by spring 133 without an intermediate lever or linkage, and prior to application of the brake, cam-face 115 of lever 100 moves lever 177 in a direction to 60 throw the motor switch to "off" position.

The end 202 of brake arm 201 may be forked or channeled, as in the case of lever 82 of Figs. 1 to 6 to cooperate with a bracket flange or 65 other guide member and resist forces tending to cause lateral displacement of the brake-arm; but this is found usually to be unnecessary, and therefore, as shown, the free end of this brake-arm is without guiding means.

To enable the brake-shoe 201 to be adjusted 70 in relation to drum 198 and especially to provide proper clearance when the shoe is in "off" position, as shown in Fig. 8, the pivot stud 204, as best shown in Figs. 11 and 12, has a portion 75 213 revolvably mounted in the bore of supporting

lug 207, and an eccentric portion 216 revolvably mounted in the end of the brake-shoe and secured in adjusted position by a set-screw 218. By rotating the stud, the brake shoe may be positioned in relation to the drum, to provide 5 the desired clearance.

While I have illustrated and described certain forms in which the invention may be embodied, I am aware that many modifications may be made therein by any person skilled in the art, 10 without departing from the scope of the invention as expressed in the claims. Therefore, I do not wish to be limited to the particular forms shown, or to the details of construction thereof, but 15

What I do claim is:—

1. In a bobbin-stripping machine, in combination, a brake to bring the machine to rest, power-unshipping devices brought into action by the brake in operating to bring the machine to rest, 20 and a cover operatively connected to apply the brake when such cover is opened.

2. In a bobbin-stripping machine, in combination, stripping devices, a guard for such stripping devices, power driving means, a brake, and 25 connections between the guard, the driving means, and the brake causing unshipping of the driving means by means of application of the brake through movement initiated by lifting the guard. 30

3. A bobbin-stripping machine having in combination means for removing waste yarn from bobbins, driving means, power-shipping means, and a brake operatively controlling the shipping means. 35

4. A bobbin-stripping machine having in combination stripping devices, driving means, power-shipping means, means enclosing such devices and including a movable portion giving access to the devices, and a brake operatively controlling the shipping means and combined with the movable portion to stop the machine when said portion is moved. 40

5. A bobbin-cleaning machine having in combination stripping devices and a cover therefor, 45 driving and braking means, and devices engaged by the cover when shut but acting to put such means in stopping relation with the driving suspended and the brake applied when no longer engaged by the cover as a result of the latter's 50 change of position when opened.

6. A bobbin-stripping machine comprising stripping mechanism, a casing having a movable cover giving access to the stripping mechanism when opened, drive-controlling means, a brake, 55 and detent mechanism cooperating with the cover in its closed position to maintain the drive-controlling means in driving position and the brake in off position, but operatively independent of the cover after the beginning of opening 60 movement of the latter, to provide for the application of the brake and the stopping of the driving.

7. A bobbin-cleaner comprising a casing having a movable cover, cleaning mechanism within the casing, driving means therefor, drive-controlling predisposed means and a brake, and means held inactive only when the cover is in closed position and acting when the cover is moved toward open position to cause a drive-interrupting movement of said drive-controlling means and to cause application of the brake to bring said mechanism to rest. 65

8. A bobbin-stripping machine comprising stripping mechanism, a casing having a movable 75

cover giving access to the stripping mechanism when opened, a drive-shaft for the stripping mechanism, means for driving the shaft, a brake-drum on the shaft, a drive-controlling member, 5 a braking member to apply braking force to the drum, means urging the drive-controlling member to non-driving position and the braking member to braking position, and a detent cooperating with the cover only when in closed position to 10 maintain the drive-controlling member in driving position and the braking member in non-braking position.

9. A bobbin-stripping machine comprising stripping mechanism, a casing having a movable 15 cover giving access to the stripping mechanism when opened, driving means, a brake, a part on the cover to act as a detent, and a cooperating detent member normally maintaining the driving means in driving position and the brake in off 20 position, the detents being operatively combined to unship the power and apply the brake when carried out of coengagement through movement initiated by the lifting of the cover.

10. A bobbin-stripping machine comprising stripping mechanism, a casing having a movable 25 cover giving access to the stripping mechanism when opened, a drive-shaft for the stripping mechanism, a fast pulley, loose pulley and brake-drum on the shaft, a belt, a belt-shifter, a brake 30 cooperating with the brake-drum, means cooperating with the cover only when closed, to maintain the shifter in driving position and the brake in off position, and means tending constantly to shift the belt to the loose pulley and apply the 35 brake.

11. A bobbin-stripping machine comprising stripping mechanism, a casing having a movable 40 cover giving access to the stripping mechanism when opened, a drive-shaft for the stripping mechanism, a brake-drum on the shaft, a motor connected to drive the shaft, a motor-controller, 45 a brake cooperating with the drum, means urging the motor-controller to off position and the brake to braking position, and means movable in a path intercepted by a part on the cover when closed and thus normally maintaining the motor-controller in driving position and the brake in off position.

12. A bobbin-cleaner comprising a casing having a movable cover, cleaning mechanism within the casing, driving means therefor, drive-controlling means, braking means for said mechanism, and means engaging with the cover only when the latter is closed and acting upon an 50 opening movement of said cover to operate said

drive-controlling and braking means to bring said mechanism to rest.

13. A bobbin-cleaner comprising a casing having a movable cover, cleaning mechanism within the casing, driving means therefor, drive-controlling means, a brake, and means normally held inactive through engagement with the cover when the cover is in closed position and acting when the cover is moved toward open position and out of engagement therewith to interrupt driving and apply the brake to bring said mechanism to rest. 5

14. A bobbin-stripping machine comprising stripping mechanism, a casing having a movable 15 cover giving access to the stripping mechanism when opened, driving means, a brake, a detent cam on the cover, and a detent lever cooperating with the cam to unship the driving means and apply the brake. 15

15. A bobbin-stripping machine comprising stripping mechanism, a casing having a movable 20 cover giving access to the stripping mechanism when opened, drive-controlling means, a brake, a detent on the cover, and a controlling member 25 cooperating with the detent and the drive-controlling means and brake to normally maintain the drive-controlling means in driving position and the brake in off position, the detent being carried by cover movement out of cooperating relation with the controlling member, whereby 30 the driving is suspended and the brake applied. 30

16. A bobbin-stripping machine comprising stripping mechanism, a casing having a movable cover giving access to the stripping mechanism when opened, driving means, a brake, a detent 35 cam on the cover, a detent lever engaging the cam when the cover is closed and controlling the operation of the driving means and brake, and means normally urging the detent lever in a direction to discontinue driving and apply the 40 brake, and effective to do so when the movement of the cover separates the cam from the lever. 40

17. A bobbin-stripping machine comprising stripping mechanism, a casing having a movable 45 cover giving access to the stripping mechanism when opened, a drive-shaft for the stripping mechanism, a fast pulley, a loose pulley and a 50 brake-drum on the shaft, a belt, a belt-shifter, a brake cooperating with the brake-drum, means urging the shifter to non-driving position and the brake to braking position, and means cooperating with the cover only when shut, to maintain the shifter in driving position and the brake in off position. 55

EDGAR A. TERRELL. 55

CERTIFICATE OF CORRECTION

Patent No. 2,009,350.

July 23, 1935.

EDGAR A. TERRELL.

It is hereby certified that error appears in the printed specification of the above numbered patent requiring correction as follows: Page 3, second column, line 67, claim 7, strike out the word "predisposed" and insert the same before "means" second occurrence in same line and claim; and that the said Letters Patent should be read with this correction therein that the same may conform to the record of the case in the Patent Office.

Signed and sealed this 10th day of September, A. D. 1935.

Leslie Frazer

(Seal)

Acting Commissioner of Patents.
